UNITED STATES PATENT OFFICE.

WILLIAM M. CROW, OF LAKEVIEW, CALIFORNIA.

ACETYLENE-GAS GENERATOR.

SPECIFICATION forming part of Letters Patent No. 657,190, dated September 4, 1900.

Application filed November 11, 1899, Serial No. 736,631. (No model.)

To all whom it may concern:

Be it known that I, WILLIAM M. CROW, a citizen of the United States, residing at Lakeview, in the county of Riverside and State of California, have invented a new and useful Acetylene-Gas Generator, of which the following is a specification.

My invention relates to improvements in acetylene-gas generators capable of embodiment in lamps and in generating plants.

One object is the construction of a generator adapted to contain within itself a water-tank, a carbide-receptacle, and the elements necessary for the generation of acetylene gas.

15 A further object is to provide improved means for feeding water by down-seepage to the carbide and to regulate the quantity of water seeping down to the carbide and the amount of gas flowing therefrom by manually-operable devices.

20 A further object is to provide means for venting the generator in case of excessive accumulation of gas in order to minimize the liability of explosion.

25 A further object is to provide means, non-metallic as well as metallic, to conduct the gas to any part of a house, hall, or other place.

The invention consists in instrumentalities 30 for attaining the above-named objects and in the construction of parts which will be hereinafter described and claimed.

In the drawings, Figure 1 is a side elevation of my improved generator embodied as 35 a portable lamp. Fig. 2 is a vertical section. Fig. 3 is an enlarged section of a part of the generator. Fig. 4 is a cross-section on the line 4-4 of Fig. 3. Figs. 5 and 6 are views in side elevation and plan of a valve-stem.

40 Like numerals denote like parts in the drawings.

One element or part of my generator is a column or shell 10, which is provided with gas-tight caps 13 14 at the ends. One cap may 45 be made stationary, while the other cap is screw-threaded or forced friction-tight by screw-pressure to a seat on the column. This single column or shell is capable of containing all the elements necessary for the generation of acetylene gas. Within the upper 50 part of the column is a water tank or vessel 25, from which water descends by down-seep-

age to carbide which is contained within a carbide-receptacle 23, the latter being arranged in the lower end of the column. This column 55 also contains a valve to control and regulate the quantity of water which passes by down-seepage from the water-tank to the carbide-receptacle, and with said valve is associated a manually-operable spindle and an intermediate valve-stem.

The element or part referred to as the "manually-operated spindle" is indicated at 43. Said spindle is cased in a gas-tight rubber sleeve 46, said sleeve being made gas-tight 65 by being secured to a solid bearing 47. The spindle works in a metallic bearing or bushing 44, which is covered by the gas-tight sleeve, and this rubber-covered bushing is forced tightly in the bearing 47 at the upper 70 end of the generator.

The element or part referred to as the "valve" is indicated at 33 as arranged to close the water-passage between the water-tank and the carbide-receptacle, and with this water-valve is combined the feed-wick 35. This feed-wick is attached to the valve to feed water by down-seepage to the carbide. The valve is provided with a spiral spring 34, which is of sufficient strength to lift said 80 valve and the valve-operating rod when the pressure is off. The spring raises the valve and opens the water-passage in order to increase the quantity of water seeping down to the carbide, and this increases the flow of gas 85 as desired. The valve, the valve-rod, and the threaded spindle all act at the same time and to the same end.

The element or part referred to as the "valve-rod" is indicated at 15 and is provided 90 with enlarged or flared ends 36 37, which serve to guide the valve-rod in its slideable play in the water-tank. The lower flared end of the valve-rod rests on top of the valve 33, while the inner extremity of the threaded spindle 95 bears upon the upper end of the valve-rod. When the threaded spindle is adjusted by turning it in one direction, the valve-rod is forced downward, and it serves to depress the valve, so as to close it in whole or in part, as 100 may be desired, whereby the valve is controlled by the manually-operable spindle, the latter working in the threaded bearing within the rubber sleeve. By this means the

quantity of water seeping down to the carbid and the quantity of gas flowing therefrom can be completely controlled.

Another element or part of my generator 5 is a vent-stopper 49, inserted into a nipple 48 on the head 14 for the purpose of venting the generator. In case of excessive gas-generation the stopper is lifted from its seat and passes gently out, relieving the generator of 10 excessive gas and making explosion impossible.

Another element of my generator is a non-metallic means for conducting gas, consisting of a rubber hose 19, which may be employed for conveying the gas to any part of 15 the house, a hall, or other place. The inner end of this hose is secured to a nipple 20 on the upper end of the generator, while the outer end of the hose is attached to a burner 20 22. The nipple 20 may have a stop-cock 21.

My generator may be embodied in a hanging lamp, or it may be constructed as a portable lamp, as shown by Figs. 1 and 2. In this adaptation shown by the drawings the 25 lamp has a base 11 and a handle 12. If desired, the cap 14 may be equipped with a plug 16, adapted to receive the burner 17, said burner having a cock 18, as shown by Fig. 2. The threaded spindle 43 has a suitable finger- 30 piece 45.

In the embodiment of the invention shown by Figs. 2, 3, and 4 the communication between the water-tank and the carbid-receptacle is cut off by the plug 26, which is inserted in the lower end of the tank and is made tight therein by the packing 27. The 35 lower part of this plug extends into the carbid vessel, and said plug is provided with a series of channels 28, which communicate 40 with ports 24, formed in the wall of the carbid-receptacle, thus permitting the gas to escape from the carbid-receptacle into a space 29, from whence the gas passes to the upper part 45 of the generator. The water-passage between the tank 25 and the vessel 23 is shown as formed by a pipe 30, embedded in the plug 26, said pipe containing the spiral spring 34 and a part of the feed-wick. The upper end of 50 this feed-wick is shown as attached to a boss 32 on the under side of the valve 33; but the employment of this tube and the boss may be dispensed with.

It is my practice to provide a packed seat for the screw-cap 13. The packing is interposed between the column and the cap, so as to be compressed between the parts and afford a gas-tight joint, which wholly overcomes leakage of the gas. By removing the cap 13 the interior carbid and water receptacles may be removed from the outer inclosing column, shell, or case 10 to enable them to be supplied with carbid and water as may be required. In practice the water-tank should be so proportioned in size to the carbid-receptacle as to hold about enough water 65 to generate all the gas the carbid charge is capable of making.

What I claim is—

1. An acetylene-gas generator, comprising a gas-tight column or outer case, the carbid-receptacle and the water-receptacle therein, the latter above the former, the feed-wick extending through an opening between said carbid-receptacle and said water-receptacle, a spring to raise said wick and the valve to 70 lower the same, and hence vary the area thereof in contact with the water in the water-receptacle, and means for controlling the movement of the valve, substantially as described.

2. In an acetylene-gas generator, the combination with the water-receptacle and carbid-receptacle, the former disposed above the latter, of a pendent water-feed wick in an opening between said receptacles a spring to raise said wick and a valve to lower the same, 75 and hence vary the area thereof in contact with the water in the water-receptacle, and means for controlling the movement of the valve, substantially as described.

3. In an acetylene-gas generator, the combination with the water-receptacle, and the carbid-receptacle below it, of the vertically-adjustable seepage-wick in the water channel or opening between said receptacle, and depending in the carbid-receptacle, whereby the 95 area of said seepage-wick in contact with the water in the water-receptacle may be varied, for the purpose set forth, and means for adjusting said wick, substantially as described.

4. In an acetylene-gas generator, the outer inclosing case forming the gas-holder, and the separable water and carbid receptacles disposed one above the other and both contained in the said outer case, said water and carbid receptacles having the plug 26 connecting 100 their meeting ends and said plug having the water-channel adapted for the reception 105 of a vertically-movable seepage-wick, and means for adjusting said wick, substantially as described.

5. In an acetylene-gas generator, the outer inclosing case forming the gas-holder, the water and carbid receptacles therein and disposed one above the other and having a communicating channel or opening, the vertically-movable seepage-wick in said opening or 115 channel, the spring to elevate said wick, the valve on the upper end of said wick, whereby the area of the latter in contact with the water in the water-receptacle may be varied 120 to regulate the quantity of water fed to the carbid, and means for moving the valve, all in combination, substantially as described.

6. In an acetylene-gas generator, in combination with the outer inclosing case forming 125 the gas-holder, the separable water and carbid receptacles located therein, the plug between said receptacles, having the gas-channels that register with gas-escape openings in the carbid-receptacle, the vertically-movable 130 seepage-wick in an opening or channel in said plug, communicating with said water and carbid receptacles, the valve on the upper end of said wick, for the purpose set forth,

and means for moving said valve, substantially as described.

7. In an acetylene-gas generator, in combination with the outer inclosing case, forming the gas-holder, the water and carbide receptacles therein, and disposed one above the other, the vertically-adjustable seepage-wick in an opening or channel between said receptacles, the spring to elevate said wick, the valve on 10 said wick, the intermediate valve-rod bearing on said rod, and the adjusting-screw extending through one side of the inclosing case, or gas-holder, and bearing on the said

intermediate valve-rod, for the purpose set forth, substantially as described.

8. The pendent, adjustable seepage-wick 15 35, having the weight-tip at its lower end, substantially as described.

In testimony that I claim the foregoing as my own I have hereto affixed my signature in 20 the presence of two witnesses.

WILLIAM M. CROW.
